UNITED STATES PATENT OFFICE.

NOAH L. VAN DORN, OF BURKET, INDIANA.

HOG-RINGER.

1,177,743.

Specification of Letters Patent.

Patented Apr. 4, 1916.

Application filed May 1, 1915. Serial No. 25,224.

To all whom it may concern:

Be it known that I, NOAH L. VAN DORN, a citizen of the United States, residing at Burkett, in the county of Kosciusko and 5 State of Indiana, have invented new and useful Improvements in Hog-Ringers, of which the following is a specification.

The present invention relates to improvements in instruments for applying rings to 10 the snouts of hogs or the like, and the object of the invention is to provide a device of this class which shall be of a simple construction, which may be easily operated, which may be regulated to compensate for 15 the different sized animals upon which the implement is used and which will perform its functions with ease, accuracy and surety.

A further object of the invention is to provide an instrument of this class primarily adapted for applying a double ring but which at the same time may be employed for the application of a single ring if desired.

A still further object of the invention is 25 to provide a novel construction of rings adapted to be applied to an animal to prevent the routing of an animal and an instrument for attaching the said ring to the animal.

30 With the above and other objects in view, the improvement resides in the construction, combination and arrangement of parts set forth in the following specification and falling within the scope of the appended 35 claim.

In the drawing: Figure 1 is a perspective view of an instrument constructed in accordance with the present invention showing the ring arranged between the jaws of 40 the instrument, Fig. 2 is a sectional view taken on a line with the slot 8', Fig. 3 is a similar sectional view taken in a line with the slots 8, Fig. 4 is a sectional view approximately on the line 4—4 of Fig. 2, Fig. 45 5 is a perspective view of the ring after the same has been operated upon by the instrument, the snout of the animal being indicated by the dotted lines, and Fig. 6 is a plan view of the ring before being operated 50 upon by the instrument.

Referring now to the drawing in detail, the numeral 1 designates an instrument in its entirety, the same comprising a pair of handles 2 and 3 respectively which are 55 formed with a reduced rounded portion 3' adjacent one of their ends, the inner faces

of said portions 3' abutting and being pivotally secured, as at 4, while projecting from each of the said reduced portions are substantially semi-cylindrical jaws 5 and 6. 60 Each of the jaws is provided with oppositely disposed approximately semi-cylindrical depressions and each of the said inner or working faces is centrally provided with a longitudinally extending arcuate 65 groove 7 and with end grooves 8 and 8', the said end grooves being slightly inclined from the outer ends thereof to the inner end, and all of the grooves terminate in a transverse, substantially rectangular de- 70 pression 9.

The numeral 10 designates the ring adapted to be operated upon by the instrument. The ring comprises two members, each being formed from a piece of wire and one 75 having its end curved, as at 11, and being provided with an approximately straight extension 12. The extension 12 of one of the members is provided with a lateral eye 13 which receives the straight extension of 80 the second member, and the curved portions 10 have their ends sharpened and arranged within the outer grooves in one of the jaws, the approximately straight ends of the portions 12 being disposed within the angular 85 end walls 14 of the end grooves of the second jaw and by compressing the handles it will be noted that the ring will be bent to the position illustrated in Fig. 5. It will be further noted that the eye is arranged so 90 as to be received within the substantially rectangular depressions 9 at the inner terminals of the grooves in the jaws, and by an arrangement as above described, it will be further noted that the ring may be applied 95 to an animal in an expeditious manner without injury to the animal as the outer edges of the jaws do not under any conditions contact with each other. The central groove receives a single ring when the device is 100 employed for attaching only a single ring, and in order that the device may be employed upon animals of varying sizes, one of the handles is provided with a set screw 105 16 which can be adjusted to contact with the inner face of the second handle.

The jaws beyond their pivots are provided with straight shoulders *a* and these shoulders when contacting prevent the outer edges or the working faces of the jaws from 110 contacting.

From the above description, taken in con-

nection with the accompanying drawing, the simplicity of the device, as well as the advantages thereof will, it is thought, be perfectly apparent to those skilled in the art to which such invention appertains without further detailed description.

Having thus described the invention, what I claim is:

A hog ringer adapted for use upon a ring comprising two members, one of which is enlarged to provide an eye whereby the other member is connected thereto, comprising a pair of pivoted jaws having inner arcuate faces, said faces being provided with

longitudinally extending parallel grooves 15 adapted each to receive one of the side members of the ring, said grooves terminating in each jaw in a substantially rectangular depressed portion adapted to receive the eye member of the ring, whereby the said eye may be forced into the said depression when the ring is bent by the ringer.

In testimony whereof I affix my signature in presence of two witnesses.

NOAH L. VAN DORN.

Witnesses:

JOHN F. KURTZ,
DARIUS L. HARSHNER.
